UNITED STATES PATENT OFFICE

JAMES A. STRUTHERS, OF MINNEAPOLIS, MINNESOTA

DESIGN FOR HOSIERY

Application filed December 19, 1929. Serial No. 33,853. Term of patent 14 years.

To all whom it may concern:

Be it known that I, JAMES A. STRUTHERS, a citizen of the United States, residing at Minneapolis, in the county of Hennepin and State of Minnesota, have invented a new, original, and ornamental Design for Hosiery, of which the following is a specification, reference being had to the accompanying drawing, forming part thereof, wherein:

Fig. 1 is a view in side elevation of an article of hosiery, showing my new design.

Fig. 2 is a view in rear elevation of the same.

The important features of the design are the elongated tongue projecting upwardly from the center of the heel portion, the stepped base of the tongue, and the spaced substantially rectangular figures at each of the longitudinal sides of the tongue substantially aligned at their outer edges with the vertical edges of the stepped portion.

What I claim is:

The ornamental design for hosiery substantially as shown and described.

JAMES A. STRUTHERS.
